ther, these numerals will be treated in accordance with algebraic usage to draw attention to the parallel function of the colors applied to the respective elements and to make the algebraic color-analogue clear, so that, for example, 2^2L and $4L$ will be synonymous and $2(5L)$ and $10L$ will equally be synonymous and will denote respectively the elements four times and ten times the length of the basic element L .

The improved apparatus according to the invention comprises a set of elements including a basic element which is a cube and a number of further elements increasing in length up to at least ten times the length of L of an edge of the basic element and thus consisting of a set of elements of L , $2L$, $3L$, $4L$, $5L$ up to at least ten; the said elements $2L$, $3L$ and $5L$ each being of a different primary color; the said elements 2^2L , 2^3L , 2^4L being each of the same primary color but in different intensities or powers of that color; the said elements 3^2L , 3^3L being likewise each of the same primary color but in different intensities or powers of that color; the set of elements including at least one element that in terms of dimensional relationship is a multiple by length of two of the elements $2L$, $3L$, $5L$ and is of a composite color produced by combining the primary colors of those two elements of which it is a multiple by length; the element L and at least one element included in the set which is a multiple of L but not a multiple of $2L$, $3L$ or $5L$, having an optical effect devoid of discernible color association with any one or more of the three said primary colors.

A basic need to fulfill the foregoing requirements is that different colors be chosen for the elements of lengths $2L$, $3L$ and $5L$ and that these be primary colors (whether or not in a tint of that primary color produced by the addition of white). By primary colors I mean colors which, however they may vary in tone, tint or shade, are in common speech described by persons of normal or average color-vision as red, blue and yellow. In the sense so defined a primary color does not lose that character merely because it has been given a particular tone by the admixture or addition of a touch of color other than white as, for example, a touch of blue in red to produce a crimson or maroon red, provided such persons would regard the color so produced as red. It would however in the sense so defined, cease to be primary if the addition of color (other than white) would lead such persons not to name it or regard it as red, blue or yellow as the case may be. Thus the addition of red to yellow in a very small quantity would be aptly described, nevertheless, as yellow, but an increase of the red component would lead such persons to call it orange or amber and to regard yellow as an inappropriate expression for the optical effect produced. It would then, under this definition cease to be a primary and become a composite color. The combination of red, as so defined, and white, which produces pink is, however, primary because such persons would regard it as a tint of red and pink is thus deemed to be red or "a red" within the definition.

The specific primary colors may be (a) a tint of the primary color red for the element $2L$; (b) a tint of the primary color blue for the element $3L$ and (c) a tint of yellow for the element $5L$, but these colors in relation to the elements in question may be interchanged. In theory they can be distributed in six permutations. In practice it is inconvenient to allocate yellow to $2L$, or even $3L$, although this is not excluded, since it is more difficult to reproduce yellow in any of the foregoing media so as to obtain the distinction in intensity desired and therefore it is highly desirable that yellow be applied to the element $5L$ as before.

It is however quite suitable to make the element $2L$ in the primary color blue and the element $3L$ in the primary color red.

It is preferred to make the element representing each power in the primary color of the prime number element in greater intensity, i.e., $L2$, pink (or light blue); $L4$ a

5

deeper red, e.g., scarlet (or a deeper blue, e.g., Cambridge blue); $L8$ a still deeper red, e.g., crimson (or a still deeper blue, e.g., indigo blue) and the element $L9$ a deeper tint of the color of element $L3$, e.g., royal blue (or a deeper red, e.g., scarlet).

In the preferred apparatus, the element $6L$ will then be a combination of the colors of $2L$ and $3L$ and the element $10L$ a combination of the colors $2L$ and $5L$.

The basic element is advantageously made white or, at least so as to present an optical effect which in the context of the colors of the set would readily be called white e.g., if the elements are of wood, it may be the natural wood color.

The element $7L$ contrary to previous practice will preferably be made of a tint of grey which being composed of black (which blots out color by extinguishing the white base of color) and white (which is the base for the display of colors and governs their intensities) so that $7L$ may be regarded as linked with the basic element of which it is a multiple but seen to have no such relationship with any other element of the set.

A set of elements from 1 cm. to 10 cm. in length, extendable from eleven to infinity (in principle) will produce a basic algebraic set.

A set may conveniently consist of twelve elements including elements $11L$ and $12L$ in which case it is preferred that $11L$ shall be a deeper grey than $7L$ (or black) and $12L$ shall be a combination of the colors of $3L$ and $4L$.

All the colors may be regarded as generated in the basic white which represents the unit from which all numbers are generated and the whole series moves in deepening tones from white, via color, to the dark area beyond the color spectrum.

The apparatus will preferably comprise appropriate numbers of each element constituting a set and the numbers of each particular element present will generally be greater for the basic element and then, progressively, lessen although not necessarily with each consecutive increase in length.

A suitable container, if desired compartmented, may be provided as part of the apparatus and compartmenting may be appropriate to the lengths of the various elements comprising a set; moreover instructional matter may be included.

One example of apparatus according to the invention will now be described.

This consists of 292 cuboid elements, each 1 square cm., in cross-section distributed in sets having lengths ranging serially from 1 cm., to 12 cm., each length having a characteristic color as set out below:

Length, em.	Color	Number of Sections
1	White.....	96
2	Pink.....	48
3	Light blue.....	36
4	Scarlet.....	24
5	Yellow.....	16
6	Violet.....	16
7	Grey.....	12
8	Crimson.....	12
9	Royal blue.....	12
10	Amber.....	12
11	Dark gray.....	4
12	Mauve.....	4
		1 292

¹ Total number.

The number of sections in the whole set and in its subsets is not a matter of principle but of educational and practical convenience.

The foregoing principles are precisely followed and the colors are operated upon throughout in purely mathematical ways to generate the color series, which is itself capable of extension beyond 12 until all the numbers generated become too dark to distinguish color.

This is capable of expression in tabular form.

Primes and powers of primes

No. series	White	Red	Blue	Yellow	Black	Composites	Color
1	1 ¹						White.
2		2 ¹					Pink.
3			3 ¹				Light blue.
4				5 ¹			Scarlet.
5					7 ¹		Yellow.
6						2×3	Violet.
7							Grey.
8		2 ²	3 ²				Crimson.
9						2×5	Royal blue.
10				11 ¹			Amber.
11						2 ² ×3	Dark grey.
12							Mauve.

It will be seen that the color factor groups are:

Primes and their powers; 1; 2, 4, 8; 3, 9; 5; 7 and 11.

Composites: 6, 10, 12, NOT being members of any group, but having affinity with two such groups.

By moving horizontally along the line of the table for any number, and using the colors in the intensities dictated by the mathematical principles involved, as shown in the columns, the correct color is obtained.

In each case, white is a component color, but, as every successive intensity of white reproduces no color change (just as $1^n=1$), the white element is progressively displaced by the addition of the appropriate color factor set out upon each line. The white content, accordingly, diminishes for each group that has more than one member shown.

The series can be extended, in principle, to infinity, e.g., $15=3×5$. The lowest intensity (or "power") of blue is combined with yellow to produce light green. $45=3^2×5$. The second intensity (or "power") of blue is combined with yellow to produce dark green. $20=2^2×5$. The second intensity of red (namely scarlet) is combined with yellow to produce a deep red-amber often described as flame-color.

But in practice the series moves into blackness and 40 indistinguishable darkness, the 15, 20, 25 . . . 100 series persisting after the rest of the numbers have lost their color-character.

Because the primary colors are treated on strictly mathematical principles as *factors* or *exponents*, the results are invariably consistent. Composite factors are seen by their color to have affinity with the prime factors they combine. Thus, violet is seen to be a color having affinities with both the red and the blue groups, and it can be seen that both these primaries are at the power of 1. Hence the white base produces the pale red/blue combination of violet, i.e., white, red, and blue, and two latter at low intensity or in mathematical terms $2'×3'×1^{2-6}$.

Since the color-factors herein chosen are factors and operate as such, the adding of color is analogous to a multiplication. Thus $2×3$ =pink+light blue, and 2^2 =the red element as found in the pink added to itself, reducing the white component to produce scarlet.

An example of a color system where the element 2L and 3L of the three elements 2L, 3L and 5L are varied in color as compared with the previous example and the consequent change of color in the other elements is the following, in a set of twelve:

- 1L --- White
- 2L --- Light blue
- 3L --- Pink
- 4L --- Cambridge blue
- 5L --- Yellow
- 6L --- Violet
- 7L --- Grey
- 8L --- Indigo blue
- 9L --- Scarlet
- 10L --- Light green
- 11L --- Dark grey
- 12L --- Mauve (a bluer mauve than in the other series)

Though the disposition of colors is changed (in relation

to the specific disposition described in the earlier example) the mathematical principles are not. There are three intensities of blue, e.g., light blue, Cambridge blue and indigo instead of two (e.g., light or Cambridge blue and royal blue) as before and two only of red instead of three. Elements 1L, 7L and 11L need not vary. Element 6L need not change if the previous tints for element 2L and 3L are not changed, e.g., can be of pale violet. Element 10L is then a light green and element 12L a rather bluer mauve than before.

It is considered that the principle of the idea is displayed by the first six elements in serial order, although the minimum set which permits display of the principle in respect of the orthodox decimal notation is a set of ten in serial from 1 to 10 and this, of course, is an important requirement for the purposes of the invention.

I have given an example previously of the numbers of each element suitable to form a complete apparatus and a probable minimum set which is useful for teaching arithmetic is approximately:

	Sections
1.—White	10
2.—Pink (or light blue)	5
3.—Light blue (or pink)	3
4.—Scarlet (or Cambridge blue)	2
5.—Yellow	2
6.—Violet	1
7.—Grey	1
8.—Crimson (or indigo blue)	1
9.—Royal blue (or scarlet)	1
10.—Amber (or light green)	1
	27

The restrictions upon educational utility in such a set 50 would, however, be severe, and the number in a set for school use cannot be reduced below the following number without seriously impairing the teaching value:

	Sections
1.—White	20
2.—Pink (or light blue)	10
3.—Light blue (or pink)	8
4.—Scarlet (or Cambridge blue)	3
5.—Yellow	4
6.—Violet	4
7.—Grey	4
8.—Crimson (or indigo blue)	3
9.—Royal blue (or scarlet)	3
10.—Amber (or light green)	10

65 The utility of the invention is not affected by mere variations in tints and shades of the same colors in the same order; and the choice of grey for the elements 7 and 11 is not critical, so long as the distinctiveness of these elements is preserved. A natural wood (not actually 70 painted white) which can reasonably be called white is likewise, not critical.

The centimeter base is not essential to the invention. The apparatus must of course be based upon a cube of a predetermined size which is then made the basis of a set of cuboids (rectangular parallelepipeds) each having

a rectangular cross-section identical to one face of the cube and lengths serially arranged as $L \times 2$, $L \times 3$, $L \times 4$, . . . $L \times 10$ (L being the length of one edge of the cube as stated aforesaid) and with the colors chosen as herein defined.

The principles involved in the present color factor series are completely different from those involved in aforesaid "Numbers in Color" system.

The colors are chosen for that system to produce a matching effect by introducing into the (differently disposed) families the key-color of the number group devised. To produce the color regarded as suitable for the purpose primaries from other groups were admixed. Thus, the red family contains brown (composed of red, blue and yellow which in my apparatus if so extended would be found in an element 30 cm. long). The blue family contains two green members (composed of blue and yellow which in my apparatus if sufficiently extended would be found in the elements 15 and 45 cm. long) and 10, incorrectly allocated to the 5 family (yellow) yields orange distinguished from yellow by a touch of red.

In the present apparatus as the colors change and deepen in their respective groups, the length and weight of the sections themselves increases in regular increments, so that the principle of relative proportions (which is the basic principle of mathematics) is displayed in three media, namely, dimension, weight and color; and all three reflect the behavior of numbers.

Briefly the set of sections from 1 cm. to 10 cm., extendable from 11 cm. to infinity (in principle) is the basic algebraic set. It extends to 10 cm., to permit its use in respect of the accepted decimal notation. It may go to 12 cm., and beyond, to study notational bases greater than 10.

Though the herein described set restricted to 12 cm. displays, in principle, the algebraic bonds implicit in the relationship of numbers to one another, its utility can be increased by the addition of identical members to each of the twelve elements comprising the basic set, as has previously herein been mentioned, and a point is reached at which further additions are in excess of what is needed for the purpose envisaged. 292 elements, disposed as set out above, are serviceable for classroom use.

What I claim is:

1. In an apparatus for teaching or studying mathematics comprising a set of elements including a basic element which is substantially white in relation to the colors of the other elements of the set and which is a cube and a number of further elements increasing in length up to at least ten times the length L of an edge of said cube, 45

50

said elements being identified as 2L, 3L, 4L, 5L, up to 10L, the improvement comprising: (1) the elements 2L, 3L, and 5L each being of a different primary pigment color, (2) the elements 2L, 4L and 8L being of the same primary color but in different intensities of that color obtained by increasing the pigment content in relation to the basic white in 4L with reference to 2L and 8L with reference to 4L, (3) the elements 3L and 9L being of the same primary color but in different intensities of that color obtained by increasing the pigment content in relation to the basic white in 9L with reference to 3L, (4) the element 6L being a composite color of the primary colors of the elements 2L and 3L, (5) the element 10L being a composite color of the elements 2L and 5L, (6) the element 7L being substantially gray and devoid of discernible color association with any of the said primary colors and related to the basic element by its white content.

2. Apparatus as in claim 1 in which the elements 2L, 3L and 5L are tints of the primary colors red, blue and yellow, respectively, and in which the colors of the elements 4L, 8L and 9L are of greater intensities than the colors of the elements 2L, 4L and 3L, respectively.

3. Apparatus as in claim 1 in which the elements 2L, 3L and 5L are tints of the primary colors blue, red and yellow, respectively, and in which the colors of the elements 4L, 8L and 9L are of greater intensities than the colors of elements 2L, 4L and 3L, respectively.

4. Apparatus as in claim 1 in which the set of elements includes an element 11L whose color is a more intense shade of gray than the color of element 7L and an element 12L whose color is a combination of the colors of the elements 3L and 4L.
